(57) **CLAIM**

The ornamental design for a digital camera, as shown and described.

DESCRIPTION

FIG. 1 is a perspective view of the front, top and right sides of a digital camera showing my new design;

FIG. 2 is a perspective view of the rear, top and left sides thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged partial view thereof in a state taking a picture; and,

FIG. 10 is a perspective view of the front, top and right sides thereof in a state of taking a picture.

The portions shown in broken lines are for illustrative purposes only and form no part of the claimed design.
